UNITED STATES PATENT OFFICE

CHARLES W. WYMAN, OF CLAREMONT, NEW HAMPSHIRE, ASSIGNOR TO SULLIVAN MACHINERY COMPANY, A CORPORATION OF MASSACHUSETTS

ELECTRICAL CONNECTING DEVICE

Application filed April 28, 1927. Serial No. 187,399.

This invention relates to electrical apparatus and more particularly from one aspect to connector devices and from another aspect to grounding systems for use with coal mining machines.

One of the objects of the invention is to provide an improved grounding system for mining machines. Another object of the invention is to provide an improved grounding system for mining machines wherein the latter are grounded in the main entry and to the transport truck in an improved manner. Still another object of this invention is to provide improved connector devices which 10 may be carried at the entry and on the transport truck whereby the motor of the machine may be supplied with electric current and the machine grounded while cutting on the mine bottom or while running about the mine on 20 its transport truck. A further object of the invention is to provide an improved interlocking connector mechanism of general application. These and other objects of the invention will subsequently more fully appear.

25 In the accompanying drawings in which I have shown for purposes of illustration one form which my invention may assume in practice,

Fig. 1 is a somewhat diagrammatic view 30 illustrating the improved grounding system incorporated in a complete cutting and transport apparatus.

Fig. 2 is in the main a central longitudinal vertical section taken through one of the improved plug connections, but a portion at the lower left hand side of the figure is broken back to an angular plane to the rear of the central plane.

Fig. 3 is a transverse vertical sectional view taken on the line 3—3 of Fig. 2.

Fig. 4 is a transverse vertical sectional view taken on the line 4—4 of Fig. 2.

Fig. 5 is a transverse vertical sectional view taken on the line 5—5 of Fig. 2.

45 In the illustrative embodiment of my invention I have shown a main entry 1 of a mine from which a room 2 projects off laterally, the entry 1 being equipped with the usual trackway 3 while the room 2 is provided with a trackway 4, all in a well known

manner. Extending along the side of the entry 1 is the usual trolley line 5 and the usual water pipe 6. As clearly shown in Fig. 1 disposed on the trackway 3 of the room 2 is a usual mining machine transport truck 7 while disposed on the mine bottom adjacent the working face of the room is a usual coal cutting machine 8 herein of a familiar electric room and pillar type.

Secured to a usual roof prop 9 is a junction or connection box generally designated 10. The junction box 10 is made up of a number of different elements as will subsequently appear. The central element of the box 10 is formed by a central rectangular block 11 of insulating material and this is adapted to be secured by transverse holding elements 12 to the roof prop 9. The block 11 has a central opening 13 within which is rotatably mounted a cylindrical insulating block 14 having secured to one end thereof a thin plate of insulating material 14^a whose purpose is later described. The members 14, 14^a are held in position relative to the central block 11 by means of hollow end members 15, 16 which have enlarged recesses 17 at their adjacent ends within which the ends of the composite member formed of the elements 14 and 14^a extend. The outer ends of the members 15 and 16 respectively carry end plates 18 and 19. The end plates 18 and 19 and the members 15 and 16 are clamped to the central block 11 by means of longitudinally extending tie bolts 20. The block 15 is provided with a bore 15^a communicating with the larger recess 17, which leaves a shoulder 15^b at its junction with the bore 17 to cooperate with the block 14. Three cylindrical bores 15^c extend longitudinally from the bore 15^a throughout the length of the block 15 and are arranged at the corners of an equilateral right prism whose edges are equidistant from the axis of the cylindrical member 15. As illustrated, the rotatable insulating block 14 has suitably secured thereto projecting fingers 21, herein three in number, each extending into one of the recesses 15^c. The plate 18 is traversed by openings each coaxial with one of the bores 15^c, two of these openings being comparatively 55 60 65 70 75 80 85 90 95 100

small and one of the full diameter of one of the chambers 15^c. The large opening is designated 18^a, the two smaller openings 18^b. A spring socket contact 22 carried within a 5 detachable plug 23 and constituting the terminal power connection is adapted to cooperate with the finger 21 in the recess 15^c with which the opening 18^a is in alinement. The handle 23 is at the end of a wire 24 10 which is connected to the spring contact member 22 at its end which enters the handle. The other end of this wire is suitably connected with a trolley fuse generally designated 25 which is connected in any suitable 15 manner with the trolley wire 5. The other fingers 21 which extend into the chambers 15^c with which communication is had through the openings 18^b are respectively connected as at 26 to wires 28 and 29, the wire 28 having 20 a return ground connection with one of the track rails while the wire 29 is clamped to the water pipe 6 and forms a ground connection for the machine.

The insulating member 14 is provided with 25 a series of chambers 14^b to which access is had through openings 14^c in the plate 14^a. These chambers are in alinement with the fingers 21 and contain spring socket contacts 30 which are in alinement with and in electrical 30 connection with the fingers 21. Fingers 31 are carried by a detachable plug 32. The plug 32 is preferably composed of two parts 33, 34 suitably held together by bolts 35. Connected to the fingers 31 are lead wires 36, 35 37, 38 which are electrically connected to the wires 24, 28 and 29 respectively when the fingers 31 lie within the resilient socket contacts 30, and the wires 36, 37, 38 are enclosed within the conductor cable 39. The 40 openings 14^c permit the passage with a very small clearance of the fingers 31.

It is undesirable for the connector plug 32 to be inserted or withdrawn while the socket member 22 is connected to the finger 45 21. These operations are precluded by means which causes the positioning of the contacts carried by the member 14 in such manner that when the fingers 31 may be inserted or withdrawn relative to the sockets 30 the socket 22 50 cannot be positioned on the finger 21. The detachable plug 23 may be locked within the junction box 10 by a transversely extending pin 40 carried by the plug and having projecting ends which are adapted to be received within slots or notches 41 extending 55 radially from the opening 18^a in the cover member 18. When the ends of the pin have been inserted through the recesses 41 and the plug rotated as is permitted by the provision of arcuate recesses 42 in the member 15 60 in communication with the notches 41, the plug 23 cannot be withdrawn and it can be withdrawn only by rotating it back to a position in which the ends of the pin 40 come 65 into register with the openings or notches 41.

To lock the plug 32 within the junction box it is provided with a radially extending pin 43 which may be inserted in a predetermined relation of the parts through a longitudinally extending notch 44 formed in the member 16 70 to such a distance that it comes opposite an arcuate recess 45 into which the pin 43 may be moved by rotation of the member 34. When the pin 43 is in alinement or registers with the longitudinal notch 44 it may be moved therethrough and the plug 32 may be inserted or withdrawn as the case may be. When, however, the pin 43 has been turned until it is engaged within the arcuate recess 45, the member 32 is locked in place. 75

A very important feature must now be noted. The pin 43 is so related to the plug 32 and the notch 44 to the chambers 15^c and opening 18^a that when the pin 43 is in registry with the notch 44 and the connector fingers 31 80 within the connectors 30, the fingers 21 are disposed distinctly eccentrically within the chambers 15^c, while when the plug 32 is rotated to bring the pin 43 substantially to the end of the arcuate notch or recess 45 the 85 fingers 21 are moved to a position coaxial with the chambers 15^c. As a result of this it will be evident that the connector member 32 can be positioned to fit its socket over the finger 21 only when the connector plug 90 32 has been inserted and turned to bring the fingers 21 into coaxial relation to the chambers 15^c, or when with the connector member 32 withdrawn the member 14 is rotated to bring the finger 21 into coaxial relation with its chamber 15^c and orifices 18^a. Now it should 95 be noted that should the connector 23 be applied and the circuit closed by connection of the fingers 21, 22 as a result of tampering with the device and turning the member 14 to make this possible, no possible chance 100 of inserting the connector plug 32 or establishing any current flow in its wires will exist. This will be obvious for the reason that until the pin 43 enters the slot 44 the fingers 31 105 cannot reach the contacts 30 so that even though the fingers may come into alinement with the sockets no circuit can be established, and if the pin is moved into the socket the fingers 31 will simply abut against the imperforate portions of the plate 14^a as the openings 14^c in these plates will lie out of alinement with the fingers 31 when the pin 43 is 110 in the slot. 115

In the normal mode of use of the plug and connector the plug will be inserted in the member 16, the pin 43 moving down the slot 44 into the same transverse plane as the arcuate recess 45. The plug 32 will then be rotated, turning with it the member 14 and as the pin 43 passes into the arcuate recess 45 the plug 32 can no longer be withdrawn. When the pin reaches the end of the arcuate recess the finger 21 will have been moved into a coaxial relation with the opening 18^a and the 120 125

connector member 23 can then be placed in position and rotated to lock it in place. Obviously the connector 23 must be withdrawn before the plug 32 can be turned in the opposite direction to permit its withdrawal and accordingly a grounding circuit will inevitably be completed whenever current flow to the truck can take place.

As shown in Figs. 1 and 2 the conductor cable 39 is adapted to be wound on the cable reel 46 suitably rotatably mounted on the rear end of the transport truck 7. The wire 36 in the cable 39 which receives current from the trolley wire 5 through the wire 24 is connected through slip ring connections, not shown, and a terminal plug to a wire 49 which is enclosed within a conductor cable 50, the wire 49 being adapted to supply current to the windings of the motor of the mining machine 8. Also enclosed within the conductor cable 50 is a return wire 51 connected through a terminal plug 52 and suitable slip ring connections, not shown, to the return wire 37 within the conductor cable 39, the return wire 37 being connected to one of the track rails through the wire 28. The ground wire 38 within the cable 39, which is connected to the wire 29 grounded on the water pipe 6, is clamped to and grounded on the reel shaft. The wire 54 enclosed within the cable 50 is grounded on the casing of the terminal plug 52 while the other end of the wire 54 is grounded on the machine frame of the mining machine 8. As clearly shown in Fig. 1, suitably secured to the side of the truck 7 is a junction or connection box 57 which is identical in structure to the junction box 10 heretofore described.

When it is desired to transport the machine 8 about the mine on its transport truck 7, the operator rotates the plug 23, unlocking the same and then removes the plug from the junction box 10. The plug 23 is then inserted within the junction box 57 on the truck. The operator then unlocks the plug 32 and removes the same from the junction box 10 and the plug is thereafter inserted within the junction box 57. When the plugs 23 and 32 are positioned and locked within the junction box 57, the return wire 37 within the cable 39 and the ground wire 38 are grounded to the side of the truck frame, as at 58, by means of wires 59 and 60 respectively. The operator then disconnects the trolley fuse 25 from the trolley wire 5 and holds the fuse in his hand in contact with the trolley wire, thus supplying current to the mining machine motor as the machine is transported on its truck about the mine. It will also be observed that the plug 23 can not be inserted within either of the junction boxes 10 and 57 until the plug 32 has been inserted and turned so as to be locked in position, thus insuring a ground connection being made before the plug 23 is inserted within the junction box.

As a result of my improved grounding system for mining machines, it will be noted that the mining machine is grounded in an improved manner both during the cutting operation and when the machine is traveling about the mine on its transport truck. It will further be noted that by the use of my improved grounding system all possibility of the operator or his helper receiving shocks, due to an insufficient ground connection is eliminated. These and other advantages of my improved grounding system will be clearly apparent to those skilled in this art.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In an electrical apparatus, a connector device comprising a casing, a member movably mounted therein and carrying a plurality of contacts a connector plug insertable in said casing on one side of said member and having contacts to engage certain of said first mentioned contacts, cooperating means on said plug and casing for preventing insertion of said plug in certain relative positions of said plug and casing, a cooperating contact carrying member insertable into said casing and having a contact to engage one of said first mentioned contacts after insertion, and means provided by said casing for preventing insertion of said second member while said plug is being inserted.

2. In an electrical apparatus, a casing having contacts movably supported therein, said casing being provided with openings through which access may be had to said contacts, and cooperating contacts adapted to be inserted through said openings and to cooperate with said first mentioned contacts, the spacing of said contacts with respect to the spacing of the openings necessitating movement of one of said first mentioned contacts by its cooperating contact after connection is made in order that the other cooperating contact can be inserted.

3. In an electrical apparatus, a casing having therein a rotatably mounted contact carrier having contacts thereon, said casing having openings through which access may be had to said contacts, cooperating contacts insertable through said openings, and means for preventing insertion of one of said cooperating contacts until after the other has been inserted and said contact carrier rotated to another position.

4. In an electrical apparatus, a casing having therein a rotatably mounted contact carrier having contacts thereon, said casing hav-

ing openings through which access may be had to said contacts, cooperating contacts insertable through said openings, and means for preventing insertion of one of said cooperating contacts while the other is being inserted including means for maintaining one of said first mentioned contacts in a position offset from the axial line of its associated opening.

5. In an electrical apparatus, a casing having openings at its opposite ends through which connector terminals may be inserted, the axes of said openings being disposed out of alinement with each other, movably supported contacts in said casing accessible through said openings, terminals connectible with said contacts, one of said contacts being movable into and out of alinement with one of said openings, and means preventing connection of one of the terminals with the other contact except when said first mentioned contact is out of alinement with its opening.

6. In an electrical apparatus, a casing having openings at its opposite ends through which connector terminals may be inserted, the axes of said openings being disposed out of alinement with each other, movably supported contacts in said casing accessible through said openings, terminals connectible with said contacts, one of said contacts being movable into and out of alinement with one of said openings, and means preventing connection of one of the terminals with the other contact except when said first mentioned contact is out of alinement with its opening, said contacts being movable after said terminal is connected to its contact to a position where said first mentioned contact is alined with its opening thereby permitting its connection with the other terminal.

7. In an electrical apparatus, a casing having openings at its opposite ends through which connector terminals may be inserted, the axes of said openings being disposed out of alinement with each other, movably supported contacts in said casing accessible through said openings, terminals connectible with said contacts, one of said contacts being movable into and out of alinement with one of said openings, means preventing connection of one of the terminals with the other contact except when said first mentioned contact is out of alinement with its opening, said contacts being movable after said terminal is connected to its contact to a position where said first mentioned contact is alined with its opening thereby permitting its connection with the other terminal, and means operative upon such movement for locking said terminal against direct withdrawal from the casing.

8. In an electrical apparatus, a casing, a contact carrier rotatable therein, alined contacts on said carrier whose axis of alinement

is parallel to but offset from the axis of rotation of the carrier, said casing having an opening whose axis lies in the surface of revolution in which the movement of said contacts takes place, a connector device having a contact adapted to cooperate with one of said first mentioned contacts insertable in said opening, said casing having a second opening in which a second connector device may be inserted to cooperate with the other of said alined contacts, and means precluding insertion of said second connector device except when said alined contacts are in a position offset laterally from the axis of said first mentioned contact device receiving opening.

9. In an electrical apparatus, a casing, a contact carrier rotatable therein, alined contacts on said carrier whose axis of alinement is parallel to but offset from the axis of rotation of the carrier, said casing having an opening whose axis lies in the surface of revolution in which the movement of said contacts takes place, a connector device having a contact adapted to cooperate with one of said first mentioned contacts insertable in said opening, said casing having a second opening in which a second connector device may be inserted to cooperate with the other of said alined contacts, and means precluding insertion of said second connector device except when said alined contacts are in a position offset laterally from the axis of said first mentioned contact device receiving opening, said casing and second connector device being further provided with means cooperating to permit rotation of said second connector device and with it said alined contacts to position the latter in alinement with the axis of the opening to receive the first mentioned connector device.

10. In an electrical apparatus, a casing, a contact carrier rotatable therein, alined contacts on said carrier whose axis of alinement is parallel to but offset from the axis of rotation of the carrier, said casing having an opening whose axis lies in the surface of revolution in which the movement of said contacts takes place, a connector device having a contact adapted to cooperate with one of said first mentioned contacts insertable in said opening, said casing having a second opening in which a second connector device may be inserted to cooperate with the other of said alined contacts, and means precluding insertion of said second connector device except when said alined contacts are in a position offset laterally from the axis of said first mentioned contact device receiving opening, said casing and second connector device being further provided with means cooperating to permit rotation of said second connector device and with it said alined contacts to position the latter in alinement with the axis of the opening to receive the first mentioned connector device.

mentioned connector device, said last mentioned means acting to lock said second connector device against direct withdrawal.

11. In an electrical apparatus, a casing, a
5 contact carrier rotatable therein, alined contacts on said carrier the axis of alinement of
said contacts being substantially parallel to
but offset from the axis of rotation of the car-
rier, said casing having an opening whose
10 axis lies in the surface of rotation in which
the movement of said contacts takes place, a
connector device having a contact adapted
to cooperate with one of said first mentioned
15 contacts insertable in said opening, said cas-
ing having a second opening in which a sec-
ond connector device may be inserted to co-
operate with the other of said alined contacts,
and means precluding insertion of said sec-
20 ond connector device except when said alined
contacts are in a position offset laterally
from the axis of said first mentioned contact
device receiving opening, said casing and
second connector device being further pro-
25 vided with means cooperating to permit ro-
tation of said second connector device and
with it said alined contacts to position the
latter in alinement with the axis of the open-
ing to receive the first connector device, said
30 last mentioned means acting to lock said sec-
ond connector device against direct with-
drawal until reverse rotation takes place and
said first mentioned connector device and
said casing being provided with means
35 adapted to cooperate to lock said first men-
tioned connector device against direct with-
drawal after connection between the same
and its cooperating alined contacts is es-
tablished.

40 In testimony whereof I affix my signature.
CHARLES W. WYMAN.
